Nathaniel Rides - Millbury, Mass.

Letter to R. D. Peabody

You probably referred to northern Bibles. I have no objection to the same containing a description of the works of the late Nathaniel Rides himself of his improvement in the construction of the various Cotton Spool or Bobbin.

With all to whom these presents shall come. Be it known that J. Nathaniel Rides of Millbury in the County of Worcester and Commonwealth of Massachusetts. Manufacturer has invented a new and useful improvement in the construction of the various Cotton Spool and Bobbin. and that the following is a full and exact description of the construction and operation of the same as invented and improved by me and described in the words following to wit.

The objection to the Spool or Bobbin as now used consists in the fact that the friction between the faces of the bobbin and the spindle on which it turns is so great that the bobbin adhering to the spindle moves with it. The result of this difficulty is that the bobbin at one time goes too fast and at another too slow. and besides destroying the work often breaks the thread. All these difficulties are removed by the introduction of my bobbin which is constructed after this manner. Instead of making the faces of the bobbin of wood or lignum vitae I make them of metal. These smaller faces are not so deep or thick as those made of wood in the common way as a consequence of this arrangement the bearing on the spindle is greatly diminished and the journal of the bobbin between the faces and the spindle the bobbin is free to follow the spindle with a motion more easy and uniform and at the same greatly accelerated. Thus by the application of these metal faces the friction between the faces of the bobbin and spindle is diminished to the very least. the bearing on the spindle is about one fourth

as much as it is in the usual mode of work in the usual way and this substance of the box being substituted is a great deal heavier. It would however be easier if the bobbins were the same in consequence of this the friction under the bobbins may be diminished by having a small cloth under and over the yarn a much lighter & easier draught - By the introduction of these metallic boxes the first term of the Money and spindle is as far removed that by the increased velocity of the bobbins together with a more regular and uniform motion, almost double the quantity of yarn may be produced.

The operation of the machine is the same as that now in use and the bobbin is of similar shape. And all I claim as my invention is the introduction of metallic boxes into the bobbins used in spinning cotton warp yarn or twisting cotton thread.
